UNITED STATES PATENT OFFICE.

ALFRED SHEDLOCK, OF NEW YORK, N. Y., ASSIGNOR TO RICHARD ESMOND.

IMPROVEMENT IN PRESSES.

Specification forming part of Letters Patent No. 149,347, dated April 7, 1874; reissue No. 6,075, dated October 6, 1874; application filed August 3, 1874.

To all whom it may concern:

Be it known that I, ALFRED SHEDLOCK, of the city of New York, in the county and State of New York, have invented certain Improvements in Presses, of which the following is a specification:

This invention relates to certain improvements in presses in which the follower is operated by the straightening of two toggle-joints drawn together by a right-and-left-hand screw.

This invention consists of a screw working through nuts, and of arms operating and acting directly as pawls within notches of the follower, as will be hereinafter described; and it further consists of a peculiar combination of parts, which are hereinafter described, and pointed out in the claims.

I will refer to the accompanying drawings, forming part of this specification, in which—

Figure 1 is a front elevation, and Fig. 2 is a plan view.

a a represent the upper parts of the toggle-joints, which have bearings in, and suspend from, the head-block *b*, the lower ends of them being pivoted to the nuts *a¹ a¹*. The lower parts *a² a²* are also pivoted to the nuts *a¹ a¹*, their lower ends being free and rounded, so as to work in the notches *c¹ c¹*, made in the extensions *c² c²* of the follower *c*, said extensions passing up and sliding in recesses made in the sides of the head-block *b*. The toggle-joints are drawn together by the right-and-left-handed screw *d*, working in the nuts *a¹ a¹*. On the middle of the screw *d* is a collar, *d'*, which fits into the grooves *c³ c³*, made in the inner sides of the extensions *c² c²*, thereby compelling the toggle-joints to move with an equal speed to or from the center line of the follower *c* upon turning the screw *d*. When the follower *c* has been forced down by the straightening of the toggle-joints, the slides *e e*, secured to the under side of the head-block *b*, are pushed into the notches *c¹ c¹*, thus holding down the fol-

lower *c*, while the toggle-joints are moved out again by the screw *d*, the pawls *a² a²* sliding out of the notches *c¹ c¹*, and being forced into upper notches by the counter-weights *a³ a³*. Upon again straightening the toggle-joints, the follower is forced farther down, and so on as far as necessary, thus doing away with all packing, besides saving considerable time. The follower *c* is shown fitting into a lard or oil hoop, *f*. The pawl-joints *a² a²* are thrown and held out of contact with the notched follower by depressing the links *g g*, which are pivoted to the lower ends of them, so that the follower may be readily raised as it is counterpoised by the weights *h h*, hanging between the rods *i i*, which connect the head-block *b* to the base *j*. The weights *h h* are attached to the follower *c* by means of ropes or chains *h' h'* passing through holes in the head-block *b* and over pulleys *b' b'*.

I claim as my invention—

1. The combination of the screw *d*, nuts *a¹ a¹*, and the pawl joints or arms *a² a²*, operating and acting directly as pawls within the notches of the follower *c*, as and for the purposes set forth.

2. The counterpoised follower *c*, in combination with a toggle-lever press, as hereinbefore set forth.

3. In a press in which the follower may be reversed independently of the operating-screw or toggle-arms, the combination of the notched follower provided with guiding-slots *c³* and a central hub, *d*, between the screws, as described, and for the purposes set forth.

4. The combination of the screw-shaft *d*, pawl toggle-joints *a²*, notched follower *c*, and weights *h h*, constructed and operating substantially as hereinbefore set forth.

ALFRED SHEDLOCK.
